CLAIM

The ornamental design for an LED light bulb, as shown and described.

DESCRIPTION

FIG. 1 is a perspective view of the LED light bulb;

FIG. 2 is a front view thereof;

FIG. 3 is a rear view thereof;

FIG. 4 is a plan view thereof;

FIG. 5 is a bottom plan view thereof;

FIG. 6 is a right side view thereof; and,

FIG. 7 is a left side view thereof.

The portions of the LED light bulb that are shown in broken lines throughout the drawings are for illustrative purposes only and form no part of the claimed design.
